US00D863395S

(12) **United States Design Patent** (10) Patent No.: **US D863,395 S**
von Fintel et al. (45) Date of Patent: ** *Oct. 15, 2019

(54) **DIGITAL CAMERA**

- (71) Applicant: **Carl Zeiss AG**, Oberkochen (DE)
- (72) Inventors: **Aaron von Fintel**, Berlin (DE); **Dominik Meier**, Munich (DE); **Franziska Haas**, Oberschleißheim (DE); **Alexander Peters**, Munich (DE); **Julia Löfller**, Munich (DE)
- (73) Assignee: **Carl Zeiss AG**, Oberkochen (DE)
- (*) Notice: This patent is subject to a terminal disclaimer.
- (**) Term: **15 Years**
- (21) Appl. No.: **29/648,303**
- (22) Filed: **May 20, 2018**
